HOSIERY-KNITTING MACHINE.

1,129,288.

Specification of Letters Patent. Patented Feb. 23, 1915.

Application filed April 11, 1914. Serial No. 831,297.

To all whom it may concern:

Be it known that we, FELIX GODIN and GEORGE P. BOSWORTH, citizens of the United States, residing at Central Falls, in the 5 county of Providence, Rhode Island, have invented certain new and useful Improvements in Hosiery-Knitting Machines, of which the following is a specification.

Heretofore it has been customary in making the high splice and the double sole, in order to provide for the reception into the fabric of the additional yarn and avoid knitting too tight at these parts, to increase the length of the stitch by drawing more 10 yarn. With our invention additional loop lengths are not drawn in making the high splice and double sole but the loop lengths, as originally drawn, are maintained and are prevented from being shortened, due to being 15 robbed of yarn by the adjacent needle or needles in these parts of the fabric where the extra yarn is introduced for making the high splice and double sole. In other words, in carrying out our invention we do not 20 draw longer loops for the high splice and double sole but on the contrary, we draw the same lengths of loops as in ordinary practice, but we maintain these lengths instead of allowing them to be shortened by 25 rendering from one needle to another and thus an additional yarn may be knit in conjunction with the main yarn, and this additional yarn may be heavier than main yarn filling up and reinforcing the fabric of the 30 high splice and double sole while the ankle and instep are knit with a single thread and without adjusting the cams to alter the lengths of the stitches at these points. In carrying out our invention, therefore, we provide as a needle raising cam, which raises the needles after they have been retracted by the usual stitch cam, one of sectional or divided form, one member of this raising cam being fixed and this serves to raise the long 35 butt needles, as in ordinary practice, which knit the ankle and instep. The other section of this divided raising cam is adjustable and by adjusting it the short butt needles which knit the high splice and the double sole may 40 be controlled so that the lengths of loops drawn by the stitch cam will be maintained

instead of being shortened by the action of adjacent needles and thus the fabric at these points will be knit of a predetermined degree of tightness.

In the accompanying drawings Figure 1 is a plan view of the cylinder and cam ring of a circular stocking machine, for instance of the Banner type. Fig. 2 is a plan view of a part of Fig. 1 with the long and short butt 45 needles indicated diagrammatically. Fig. 3 is an end view looking from the left of Fig. 1 of so much of the machine as is necessary to an understanding of our invention. Fig. 3^a is a detail sectional view. Fig. 4 is a developed view of the cam ring with the adjustable part of the divided needle raising cam in normal position for making the leg. Fig. 5 is a view like Fig. 4 with the adjustable part of the divided raising cam in position for making the high splice and double 50 sole.

One of the stitch cams is shown at 1, this being the cam which is operative during round knitting. The other stitch cam 2 is 55 operative together with the cam 1 during reciprocating knitting, as is usual in the Banner type of machine, and the usual guard cam is shown at 3. The narrowing picks 3' and the widening picks 3'' may be 60 substantially the same as in ordinary practice. The needles during round and round knitting move in the direction of the arrow in Figs. 1, 2, 4 and 5 and are advanced to take yarn by riding over the cam 2 and are 65 retracted by the stitch cam 1, after which they are raised to the normal plane by the lifting cam 4, forming a part of the cam ring 5. This lifting-cam is formed in two sections, as above described, the inner section 7 being adjustable and this adjustment, in the example of our invention illustrated, takes place circumferentially of the machine. The other section, *i. e.* the outer one, is fixed.

When the inner adjustable section 6 is in 70 the normal position shown in Figs. 1, 2 and 4 with its inclined edge in the same plane with the inclined edge of the fixed outer section 7, these sections will raise all the needles immediately they have cast their 75 stitches, as will be seen from the dotted line $x-x'-x$, indicating a part of the knitting 80

wave in Fig. 4. The needles therefore reach their retracted position x' in succession and singly and each needle when it reaches this position robs the preceding needle, which is now rising, of a portion of its yarn and thus makes the stitch shorter than the length originally drawn over the nib of the web holder, this action being of course calculated or allowed for by the operator who adjusts 10 his cams accordingly to make the fabric of the desired degree of tightness.

With our improvement, the ankle or instep needles, *i. e.* the long butt needles *a*, Fig. 2, are controlled in the ordinary way, rising 15 as soon as they have drawn their stitches which are therefor produced of the desired length in the ordinary way by properly adjusting the cam ring in relation to the needle cylinder. The short butt needles *b*, 20 which make the high splice and double sole, are however, specially controlled where these parts of the stocking are knit, and for these purposes we make the section 6 of the cam ring shiftable circumferentially of the needle cylinder, as above mentioned, and outside of this is provided the fixed section 7 whose incline conforms in degree to that of the shifting section. Both of these sections of the lifting cam are mounted upon 25 the cam supporting plate II of the Hemphill Patent No. 933,443, the fixed section having a base flange held by screws 8 and the shifting section has a flange 9 held by screws 10 passing through slots thereof into said plate 30 H. The shifting section 6 is of a thickness to act upon the short butt needles *b*. The long butts *a* of the instep needles project over this edge and are acted upon by the incline of the fixed lifting cam section 7 but 35 not so the short butt high splice and sole needles. When now the high splice and the double sole are to be knit the shifting cam section 6 is moved leftward circumferentially from the position shown in Fig. 4, 40 which is a view looking from the inside of the cam ring outward, so that it will assume the position relative to the fixed cam section 7, as shown in Fig. 5, leaving this fixed section still exposed for the long butt needles 45 to ride up at once following their retraction so that the usual knitting action will take place on the long butt needles, *i. e.* each needle after it has drawn its loop and begins to rise will be robbed of a part of its 50 yarn by the next needle as this is reaching its extreme retracted position, the knitting wave of the long butt needles being that shown in Fig. 5 at x , x' , x^2 during the knitting of the ankle and instep on the long butt needles. The short butt needles, however, 55 will have a knitting wave like that indicated at x , x' , x^3 , x^4 in Fig. 5, that is to say by reason of the cam section 6 having shifted leftward to the position shown in Fig. 5

these short butt needles will not immediately rise after being retracted but will remain down (see the knitting wave at x' , x^3) and hold their stitches and maintain their length while the next one or two needles are drawing their stitches, and thus the needles 65 will not be robbed of any of the yarn which they have drawn and while they do not draw longer loops their loop lengths are maintained and provision is thus made for the fabric being filled by the additional yarn 70 without any looseness appearing in the instep or ankle and without extra tightness in the high splice or double sole.

The drawings, Figs. 1, 2, 3, and 4, show the parts in the position for knitting the 80 leg, heel and toe in the regular way, the shifting cam section 6 being in normal position with its inclined edge in the same inclined plane with the inclined edge of the fixed cam section 7. This will make the leg 85 with all the stitches alike throughout the tube. Fig. 5 shows the position of the parts during the formation of the high splice and double sole, the line $x'-x^2$ indicating the upward course of the long butt needles due 90 to cam section 7 and the line $x'-x^3$ indicating that the short butt needles do not immediately rise after drawing their loops but remain down until they strike the edge of the cam 6 which has been shifted circumferentially so that the loop lengths drawn by these needles will be maintained. For operating this shifting cam section or rather for holding it in the position shown in said Figs. 1, 2, 3 and 5 for regular knitting 100 without reinforcing, the flange of the cam slide has screwed thereto a projection 11 which is borne upon by a finger 12 on a rock shaft 13 journaled in the post 14 and having an arm 15 connected by a link 16 105 with a lever 17 pivoted to the frame at 18 and having its front end controlled by a cam 19 mounted on the shaft *s'* of the pattern drum of the Hemphill patent. This cam has a high part *c* for the leg, a low part 110 *d* for the high splice, a high part *c* for the heel and a low part *f* for the foot. While the lever is on the high parts the shifting cam section 6 will be held in normal position to do knitting in the ordinary way and 115 with a single yarn. When the reinforcing yarn is thrown in by the mechanism common, for instance, in the Hemphill patent and machine the lever 17 falls into the low part *d* or *f* of the controlling cam, a spring 120 20 gives this effect. This retracts the finger 12 from the stud or projection 11 and allows the shifting cam section 6 to move circumferentially, under pressure from the short butt needles, until the projection 11 comes 125 against the stop arm 21 fixed adjustably to the base flange of the cam ring. The shifting cam section 6 will then have assumed the

position shown in Fig. 5 in relation to the fixed cam section 7 which operates the long butt needles, and therefore the effect above described will be secured, the stitches in the high splice being maintained of the length in which they were originally drawn so as to provide for the extra filling resulting from the reinforcing thread being knit at the same time with the main thread, while on the long butt needles the stitches will be formed in the usual way to provide a fabric of the desired length of loop and tightness for the ankle or instep. After the high splice is knit the shifting cam section 6 is shifted back again to normal position through the connections described when the cam lever 17 rises onto the high part marked *e* for the heel, and following this the cam lever will fall into the low part of the cam 19 and the shifting needle cam section 6 will be adjusted into the relation of Fig. 5 for knitting with the main and reinforcing yarns as above described.

We have shown a cam 22 for making a mock seam in the fabric along the high splice and foot, this cam co-operating with two long latch needles, not shown, which are situated at diametrically opposite points in the needle circle and which are long butt needles. This cam is raised during the knitting of the leg so that both long latch needles after receiving the yarn and casting off will be raised by this cam high enough to make the new loop fall below the latch and thus when it takes yarn again and retracts this loop will be cast off and as this happens on both long latch needles plain fabric will be formed throughout the entire circle of needles. If, however, the long latch needles are not elevated to make the loop get back of the long latch they will form a tuck stitch in the ordinary way, and this tuck stitch appearing on the same wales at opposite side of the tube will give the appearance of a seam. In this operation, therefore, the cam is held down for one revolution of the cylinder to get two stitches on each long latch needle and at the next revolution the two stitches are cast off, thus forming the tuck stitch.

For holding the cam up during the knitting of the leg to make plain fabric, a link 23 is connected to the same cam lever 17 which operates or controls the shifting needle cam section 6 so that as long as this cam section is in normal position, *i. e.* for knitting the leg or heel, the cam 22 will be up and plain fabric will be knit. This is due to the link 23 pulling down upon the arm of a lever 24 pivoted at 25 and connected with a vertically movable rod 26 which, through an arm 27 having a fork engaging a pin 28 on the vertical adjustable cam 22, holds this up. While the said cam

is held up as just described, the roller 29 65 on arm 30 fixed to the shaft 25 of the said lever 24, is also held up out of the path of cam blocks or segments 25, 26 on the gear wheel 7, which is correspondingly marked in the Hemphill patent. When, however, 70 the reinforcing yarn is thrown into work the needle cam section 6 shifts to the position shown in Fig. 5 by reason of the low part of the cam coming beneath the cam lever and at the same time the link 23 rises 75 and releases the lever 24, it being connected thereto by a pin and slot 31, and thus the roller on the arm 30 connected with said lever will fall into the path of the cam segments or blocks 25, 26 on the gear, and thus 80 the vertically adjustable long latch needle cam 22 will be alternately raised and lowered during the knitting of the high splice and foot and the mock seam will be formed by the long latch needles. The needle cylinder makes four turns to one revolution of the gear wheel and therefore the two cam blocks or segments 25, 26 are used on the gear with corresponding number of spaces between. These blocks and spaces each occupy approximately one fourth revolution 85 of the gear. Therefore, while one pattern block 25 or 26 is passing the roller of the lever 24 the needle cylinder will rotate once and both of its long latch needles will be 90 raised to make their loops fall below the latches for casting off when these needles retract, whereas when the spaces between the cam segments 25, 26 are passing the roller the knitting head will make a revolution and take a new feed of yarn but the long latch needles will not be advanced by the cam 22 because this is now down and consequently the old loops will be held on the latches, together with the new loops and 95 when these are cast off together the tuck stitch will be formed. It will be seen therefore that the cam 22 is controlled by the same lever 17 that controls the shifting needle cam section 6 and that it is released 100 from this control at times to permit its control by the cam blocks 25, 26 and spaces of the gear wheel, this release being due to the slot 31 in the link 23 which allows the lever 24 to be worked by the cam blocks and 105 spring when the link is raised at the time the cam lever falls into one of the spaces of the cam wheel.

We claim as our invention:

1. In a circular stocking knitting machine, 120 long butt needles occupying one half of the needle circle, short butt needles occupying the other half of the needle circle opposite the first half, a stitch cam for retracting the needles to draw stitches and to cast off old 125 loops, and a needle raising cam with means for adjusting said cam to vary the point of raising the short butt needles in relation to

their travel and to the stitch cam, and to the point of raising the long butt needles, substantially as described.

2. In a circular stocking knitting machine, a series of long butt instep needles, a series of short butt heel and toe needles which knit also the high splice and double sole, a stitch cam for retracting the needles to draw stitches and to cast off old loops, 10 and a needle raising cam in two portions, one portion being fixed and operating upon the long butt instep needles and a second portion lying within the circle of the fixed portion and receiving only the short butt 15 heel and toe needles to raise them after drawing their loops; said second cam portion being adjustable to vary the point it will begin raising the short butt needles following the loop drawing action for maintaining loop lengths in knitting the reinforced part of the fabric, and means for automatically adjusting said needle raising cam.

3. In combination in a circular stocking 25 machine, a set of long butt instep needles occupying one-half the needle circle, a set of short butt needles occupying the opposite half of the needle circle and a two part needle raising cam, one part of which is arranged within the other, the outer part operating upon the long butt needles and the inner part operating upon the short butt needles and one being adjustable in relation to the other to vary the relative points 30 at which said portions begin raising the long and short butt needles and thereby maintaining the lengths of the loops drawn by the short butt needles, substantially as described.

4. In combination in a circular stocking machine, a set of long butt instep needles, a set of short butt heel and toe needles, each set occupying its own half of the needle circle, a stitch cam, a two part needle advancing cam following the stitch cam, one of said cam parts lying within the other, the inner part acting on the short butt needles and the outer part on the long butt needles, and means for automatically adjusting the inner cam part circumferentially of the needle row to vary the point that it will begin to advance its needles.

5. In combination in a circular stocking knitting machine, long and short butt needles, a stitch cam, a two part needle lifting cam following the stitch cam, the inner part raising the short butt needles and the outer part being fixed and raising the long butt needles, said inner part being guided to move under pressure from the needles, when released, to a position to maintain the loop lengths, and pattern controlled means for moving the said cam back to normal position.

6. In combination in a circular stocking 65 knitting machine, long and short butt needles, a stitch cam, a two part needle lifting cam following the stitch cam, the inner part raising the short butt needles and the outer part being fixed and raising the long butt 70 needles, said inner part being guided to move circumferentially of the needle cylinder under pressure from the needles when released, and pattern controlled means for moving the said cam back to normal position, 75 said pattern controlled means comprising a projection extending from the cam, a finger engaging said projection and a pattern lever with connections to said finger for operating the same, substantially as described.

7. In combination in a stocking knitting machine, a needle cylinder, a set of long and a set of short butt needles arranged in two sets at diametrically opposite points of the 85 cylinder, a two part cam both parts of which elevate the needles after casting their loops, one part elevating the short butt needles and the other part elevating the long butt needles, and means for adjusting the 90 cams to vary the time at which the short butt needles will begin to elevate in relation to the time at which the long butt needles will begin to elevate, substantially as described.

8. In combination in a circular stocking knitting machine, long and short butt needles, a two part raising cam for said needles comprising an inner part operating on the short butts and the outer part operating 100 upon the long butts, means for adjusting the inner cam part in relation to the outer part, an advancing cam for operating a pair of long latch needles on opposite sides of the needle circle, and means for adjusting said 105 advancing cam substantially simultaneously with the adjustment of the inner cam member of the two part needle raising cam.

9. In combination in a circular stocking 110 knitting machine, long and short butt needles, a two part raising cam for said needles comprising an inner part operating on the short butts and the outer part operating upon the long butts, means for adjusting the inner cam part in relation to the outer 115 part, an advancing cam for operating a pair of long latch needles on opposite sides of the needle circle, and means for adjusting said advancing cam substantially simultaneously 120 with the adjustment of the inner cam member of the two part needle raising cam, both of said adjusting means including connections to a pattern controlled lever common to them both, substantially as described.

10. In combination in a circular stocking 125 knitting machine, long butt and short butt needles, a two part raising cam for the needles comprising an inner part for raising

short butt needles and an outer part for raising long butt needles, an advancing cam for long latch needles having long butts, means for raising and lowering said advancing cam including a controlling lever and cam projections with a revolving carrier therefore, a pattern lever, a pattern cam for operating the same, a connection from the pattern cam to the adjustable member of the 5 two part cam and a connection from the said pattern lever to the controlling lever

for placing the same in or out of operation relative to the cam projections of the rotary carrier, substantially as described.

In testimony whereof, we affix our signatures in presence of two witnesses.
